IGNITION DEVICE OR SYSTEM FOR GAS AND LIQUID FUEL BURNERS

Casper S. Stuckenholz, Cleveland, Ohio, assignor to The W. J. Schoenberger Company, Cleveland, Ohio, a corporation of Ohio

Application March 13, 1941, Serial No. 383,222

5 Claims. (Cl. 175—115)

This invention relates to ignition devices or systems for gas and liquid fuel burners.

Heretofore it has been the practice to provide a pilot burner adjacent the main burner for lighting the latter. This pilot burner heats an operating element which in turn actuates a gas valve controlling the main gas supply to the burner. This gas valve, preferably located adjacent the main burner, is in addition to the main shut off valve or gas cock.

One of the objects of this invention is to provide an electric ignition system in which the auxiliary gas valve now in use will be eliminated.

Another object of the invention is to provide an efficient electrically operated latch means for preventing actuation of the main shut off valve or gas cock to the position in which gas is supplied to the main burner, until after the pilot has been lighted, wherein an ignition circuit including a heater coil and a bi-metallic switch in parallel with an ignition coil, is employed.

Still another object of the invention is to provide means whereby the gas valve can be returned to off or closed position from full flow position when the flow of current to the electrically operated latch is shut off and the latch is in position to prevent actuation of the valve to full flow position.

Other objects and advantages of the invention will be apparent as the ensuing description is considered in connection with the accompanying drawing, in which:

Figure 1 is a side view of the gas valve and parts associated therewith;

Figure 2 is a plan view of the main burner and parts associated therewith;

Figure 3 is an end view of the gas valve showing the valve in closed position with the circuit open;

Figure 4 is a view similar to Figure 3 but showing the bi-pass open and the electric circuit closed;

Figure 5 is an end view showing the valve in full open position, with the pilot lit and the circuit open; and

Figure 6 is an end view of the latch arm.

Referring more particularly to the drawing 1 denotes the front plate or panel of a gas stove or range. For purposes of illustration the range is shown as having an oven burner 2, but it will be understood that the present invention is equally adaptable for use with top or other burners for gas appliances.

A gas cock 3, suitably mounted upon a gas supply pipe or manifold 4, connects at its inner dis-

charge end with the air and gas mixing chamber 5, of the burner 2, through the medium of a conduit or pipe 16, and at its other end is provided with an operating stem 6 which projects freely through an aperture 7 formed in the panel 1. A latch member 8 secured on the stem 6 of valve 3 is formed with oppositely extending arms 9 and 10, the end of the arm 9 being provided with a beveled latch member 11 while the arm 10 carries an electrical contact member 12. These members 11 and 12 are adapted to co-operate with a bi-metallic stop member or strip 13 and an electrical contact member 14, the latter two of which members being carried by a bracket 15 in turn suitably supported upon the valve 3. Electrical contact members 12 and 14 are suitably insulated from the arm 10 and bracket 15 respectively.

Positioned adjacent certain of the gas ports 35, of the burner 2, is a pilot 17 which receives a reduced supply of gas from the valve 3 when the gas cock handle 18 is appropriately manipulated, in a manner presently described. Two coils 19 and 20 positioned in proximity to the pilot 17 and bi-metal strip 13 respectively, are provided, the former for igniting the pilot burner and the latter for heating the strip 13, when an auxiliary electric circuit is completed through the closing of a bi-metallic switch 31. This switch 31 is in series with two parallel circuits including the two coils 19 and 20, contact points 12 and 14 being employed to control the entire circuit.

The hollow valve casing 21 has an interior tapered bore 22 which rotatably receives a tapered valve plug 23, having therein a transverse full flow passageway 24, adapted for registry with an inlet bore or passageway 25, formed as a part of the housing and a communicating longitudinal passageway 26 which is at all times in communication with the outlet passageway 27. The communicating passageways 24 and 26 of the valve plug just referred to are the main passageways and are utilized when either a full flow or a reduced flow of a fuel is desired at the main burner. The casing is also formed with an inwardly and upwardly extending bi-pass 28 leading from the casing inlet passageway 25 and opening into the casing bore 22 at a point inwardly spaced from the inlet passageway. An annular groove 29 formed in and extending almost completely around the plug is adapted to be brought into registry with the outlet end of the bi-pass 28 for supplying a small quantity of gas to the pilot 17. Thus the groove 29 is also

adapted to place the bi-pass in communication with a small transverse outlet opening or passage 30 extending through the casing wall in the same vertical plane with but spaced from the outlet end of the bi-pass 28 approximately 45°. The small gas pipe 31 connected at one end to the small outlet port 30 and at its other end to the pilot 17, supplies gas to the latter when the groove 29, bi-pass 28 and port 30 are in communication with each other.

When the burner is not in use, both coils 19 and 20 are cold and the bi-metal strip 13 assumes a position in the path of travel of the latch member 11, carried by the arm 9, thus making it impossible to open the gas valve 3 sufficiently to supply gas to the main burner. However, movement of the valve plug in a clockwise direction from off or Figure 3 position, through a small predetermined arc, to Figure 4 or bi-pass flow position is possible, before the latch member 11 engages the bi-metallic stop member. In this latter position the inlet passage 24 in the plug is still out of communication with casing inlet passage 25, but bi-pass 28 as well as outlet port 30 is in communication with the passage 25 and permits a small flow of gas to the pilot. At the same time, the contacts 12 and 14 are closed by rotation of the valve and current flows to the ignition coil 19 through wire 32 leading from one side of a battery 33 to and through closed contacts 12 and 14 and thence through wire 34 to one end of the ignition coil and finally to the other side of the battery through wire 36. Although the ignition coil 19 soon becomes hot and ignites the pilot 17, the bi-metallic strip 13 remains in the path of movement of the beveled latch member 11 and blocks movement of the valve to full open position until a bi-metallic safety switch 37 is closed.

The switch 37 comprises insulated bi-metallic strips 38 and 39 having electrical contacts 40 and 41 respectively. The switch 37 being in series with heater coil 20 but in parallel circuit with ignition coil 19. After the pilot light has been ignited by the coil 19, the former soon heats the strips 38 and 39 and causes the contacts 40 and 41 to close. Current will then flow from the battery through wire 32 to contacts 14 and 12 and thence through wires 34 and 43, the latter leading to one end of heating coil 20. The current flows from the other end of coil 20 through a wire 43 to metallic strip 38 and thence through the switch 37 to and through wires 44 and 36 back to the battery 33. The coil 20 now heats the bi-metallic strip 13 and causes the latter to move out of the path of rotation of the beveled latch member 11, thus permitting the rotation of the valve to open position, for supplying gas to the main burner which is ignited by the pilot burner. In moving the valve to open position, the valve contacts are separated, shutting off current to both coils and permitting the bi-metallic strip 13 to cool off and resume its normal position in the path of movement of the latch member 11. However, in turning the burner valve in an anti-clockwise direction back to closed position, the beveled or wedge-shaped face 45 of the latch part 11 rides freely over the offset end of the bi-metallic strip 13 and does not interfere with the closing of the valve. During the turning of the valve in a counterclockwise direction to off or closed position, a full flow of fuel to the pilot 17, through the groove 29, is assured until the main burner is completely shut off.

When the invention is used with a gas range having a top burner pilot lighter the pilot 17 could be ignited by means of a flash tube (not shown) so positioned as to light the pilot 17 when its raw gas supply is conveyed through said tube to be ignited by the top burner pilot, whereby the ignition coil 19 could be eliminated.

Having thus described my invention, what I claim is:

1. An apparatus of the kind described comprising in combination with a main burner, a pilot adjacent the burner for lighting the same, a source of fuel supply, a rotary valve adapted to open and close passage of fuel from said source of supply to said main burner and pilot, a bi-metallic latch for temporarily preventing further movement of the valve after the valve has been rotated to position to supply fuel to the pilot, an ignition circuit including an ignition coil, an auxiliary circuit including a heating coil and a bi-metallic switch in parallel with said ignition coil, said ignition coil adapted to light the pilot and the bi-metallic switch adapted to be heated by the pilot to close the auxiliary circuit whereby the bi-metallic latch will be heated and moved to an inoperative position when the main circuit is closed, contact members associated with the valve for closing the ignition circuit upon movement of the valve to a position to supply fuel to the pilot, said contact members being opened to break the ignition circuit when the valve is moved to a position to permit of a full flow of fuel to said main burner whereby the heater coil circuit is broken and said bi-metallic latch will cool and return to operative valve latching position.

2. An apparatus of the kind described comprising in combination with a main burner, a pilot adjacent the burner for lighting the same, a source of fuel supply, a rotary valve adapted to open and close passage of fuel from said source of supply to said main burner and pilot, a latch for temporarily preventing further movement of the valve after the valve has been rotated to position to supply fuel to the pilot, an ignition circuit including means for lighting the pilot when the ignition circuit is closed and said means is energized, an auxiliary circuit including means for actuating the latch and a switch in parallel with said pilot lighting means, said pilot lighting means adapted to light the pilot and said switch adapted to be affected by the pilot to close the auxiliary circuit whereby the latch actuating means will be energized to move the latch to an inoperative position when the main circuit is closed, contact members associated with the valve for closing the ignition circuit upon movement of the valve to a position to supply fuel to the pilot, said contact members being opened to break the ignition circuit when the valve is moved to a position to permit of a full flow of fuel to said main burner whereby the auxiliary circuit will be broken and said latch actuating means will become de-energized and the latch will return to operative valve latching position.

3. An apparatus of the kind described comprising in combination with a main burner, a pilot adjacent the burner for lighting the same, a source of fuel supply, a rotary valve adapted to open and close passage of fuel from said source of supply to said main burner and pilot, a bi-metallic latch for temporarily preventing further movement of the valve after the valve has been rotated to position to supply fuel to the pilot, an ignition circuit including means for lighting

the pilot, an auxiliary parallel circuit including means for heating the latch to move the same to an inoperative position when the auxiliary circuit is closed and means in said auxiliary circuit adapted to hold said circuit open until after said pilot is lit and to close the same after the pilot is lit, and contact members associated with the valve for closing the ignition circuit upon movement of the valve to position to supply fuel to the pilot, said contact members being opened to break the ignition and auxiliary circuits when the valve is moved to position to permit of a full flow of fuel to said main burner whereby flow of current to the latch heating means will be closed and said bi-metallic latch will cool and return to 10 operative valve latching position.

4. An ignition system of the kind described including in combination with a main burner, a source of fuel supply, a pilot burner for ignition of the main burner, a valve for controlling the flow of fuel to said pilot and main burner, means for operating said valve, a latch for temporarily preventing more than a predetermined movement of said valve so as to temporarily provide fuel to the pilot only, an electric ignition circuit 15

including switch means operating in conjunction with said valve for opening and closing the circuit, said circuit also including ignition means for igniting the pilot and switch means for rendering inoperative the latch for temporarily preventing full operation of said valve after the pilot flame has been established.

5. An ignition system of the kind described including in combination with a main burner, a source of fuel supply, a pilot burner for ignition of the main burner, a valve for controlling the flow of gas to the pilot and main burner, means for operating the valve, locking latch means for temporarily preventing more than a predetermined movement of said valve so as to temporarily provide fuel to the pilot only, an electric ignition circuit including switch means operating in conjunction with said valve for opening and closing said circuit, said circuit also including 20 switch means for rendering said locking latch means inoperative so that said valve can be operated to full open position after the pilot has been lit and means for igniting the pilot.
